The ornamental design for a display screen having a graphical user interface, as shown and described.

DESCRIPTION

FIG. 1 is a front view of a first embodiment of a display screen having a graphical user interface; and,

FIG. 2 is a front view of a second embodiment of a display screen having a graphical user interface.

The broken line showing of a display screen and elements of the graphical user interface are included for the purpose of illustrating portions of the article and form no part of the claimed design.
